UNITED STATES PATENT OFFICE.

VICTOR DE BUCK, OF BRUSSELS, BELGIUM.

CIGAR.

SPECIFICATION forming part of Letters Patent No. 684,413, dated October 15, 1901.

Application filed October 15, 1900. Serial No. 33,100. (No model.)

To all whom it may concern:

Be it known that I, VICTOR DE BUCK, a subject of the King of the Belgians, and a resident of Brussels, Belgium, have invented certain new and useful Improvements in Cigars, of which the following is a specification.

This invention relates to a cigar of novel shape and construction, the manner of manufacturing which is hereinafter explained.

In the accompanying drawings, Figure 1 shows in section a cigar-bunch having a fillet or string of long-filler tobacco laid lengthwise therein and extending beyond the two ends of the bunch. Figs. 2 to 7 show the new cigar, the body of which may be of square, triangular, octagonal, hexagonal, or rectangular section. Figs. 8 to 13 are end views of the different-shaped cigars shown in Figs. 2 to 7, taken consecutively. Figs. 14 and 15 are plan views of two molds, showing in section a bunch provided with its central fillet of tobacco. Figs. 16 and 17 represent reductions of the two molds shown in Figs. 14 and 15, respectively. Figs. 18 and 19 show modifications of the mold.

A fillet or string *a a* of tobacco distinct from that which constitutes the body of the cigar is so arranged that it will extend the whole length of the latter. This fillet rests in a bunch *b b*, shortened at both ends or only at the lower end. This shortened bunch is then introduced into a mold *c*, open at both ends, or a mold *d*, open only at the lower end, such as shown in Figs. 14, 15, 18, and 19, or any modification thereof may be adopted.

According to the usual method of manufacturing cigars the mold receives and shapes the whole bunch; but according to the present invention the mold receives and shapes only the shortened bunch—that is to say, the body of the cigar—leaving the head as well as the pointed end outside it quite untouched. This permits the desired shape to be given to the cigar and also prevents any crushing of the head and pointed end. The latter is an evil which frequently occurs in the ordinary method of manufacture and causes an obstruction in the draft of the cigar, especially in cigars with pointed ends. Moreover, in

order to provide a longer pointed end and a better-looking cigar, together with a perfect draft, this end is not specially wrapped, but is inclosed only in the wrapper which covers the bunch proper of the cigar.

The method employed, as above described, gives a bold well-defined shape to the cigar and a very long tapering end without lessening the draft, the body of the cigar bulging out abruptly and being well filled in contrast to the end parts.

In order to give the cigar a distinctive appearance and to insure regular combustion, it is pressed into triangular, square, hexagonal, or octagonal prismatic shape, as represented in Figs. 2 to 13. In consequence of the fact that a shortened bunch surrounds an internally-arranged longer fillet or string *a* and that the whole is covered by a wrapper wound around the said bunch, the pressure above described gives to the body of the cigar at the tapering ends thereof a semicircular line of demarcation, as at *f* in Fig. 7, or a pointed arch, as at *g* in Figs. 2 to 6, forming thus a number of flat faces, as it were, which, with the edges of the three, four, six, or eight sides, give to the cigar a prismatic form. The form of a pentagonal prism may be adopted.

As may be seen from the drawings, the plane of pressure *h h* will determine the extremity of the semicircular or the pointed arch-line of demarcation, the cigar shown in Figs. 2 to 6 corresponding to the mold 15 and the sample represented by Fig. 7 will correspond to mold 14.

One of the numerous advantages of the cigar described is that it is, so to speak, built up regularly. Owing to the pressure being in a prismatic form, the operator must proceed systematically. The shape of the article produced would betray any negligence in the work. Moreover, the fact that the wrapper covers a shortened bunch having a thread or fillet of tobacco passing through it longer than itself the smoker enjoys two successive and distinct flavors.

Having fully described my invention, what I claim, and desire to secure by Letters Patent, is—

1. A cigar having a central longitudinal fillet of long-filler tobacco, surrounded by a shortened compressed bunch, leaving at least one end of the fillet projecting and uncom-
5 pressed, and a wrapper covering the whole.
2. A cigar having a central longitudinal fillet of long-filler tobacco surrounded by a shortened compressed bunch, leaving the pro-
jecting end or head of said fillet as well as a

pointed end uncompressed, the whole being to covered by a wrapper.

In testimony whereof I have hereunto set my hand in presence of two witnesses.

VICTOR DE BUCK.
